UNITED STATES PATENT OFFICE.

LOIS M. UNDERWOOD, OF DAYTON, OHIO.

FURNACE GAS-PRODUCER.

1,337,298.

Specification of Letters Patent. Patented Apr. 20, 1920.

Application filed March 10, 1919. Serial No. 281,613.

To all whom it may concern:

Be it known that I, LOIS M. UNDERWOOD, a citizen of the United States, residing at Dayton, in the county of Montgomery and State of Ohio, have invented a new and useful Improvement in Furnace Gas-Producers, of which the following is a specification.

My invention relates to new and useful improvements in kilns and more especially to an individual gas producer chamber or compartment which is a unitary part of the kiln structure, and to a removable twyer which is placed in said compartment to produce the gas and is thereafter removed from said compartment and placed in that of another kiln to perform the same function until all of the kilns are supplied with the necessary gas for the operation.

The invention is applicable to a single kiln or any number of kilns arranged *en bloc*, where each individual kiln is provided with this gas producer chamber or compartment.

The object of the invention is to provide a kiln or each individual kiln, where there are a number arranged *en bloc*, with its own individual gas producer chamber, and a twyer which is adapted to be used in the gas producer compartment of each kiln and removed to another after each kiln is supplied with producer gas sufficient for burning the ware therein.

A further object of the invention is to provide means in each kiln for supplying the gas produced with a suitable amount of additional air, as the said gas passes from the producer chamber or compartment into the combustion chamber of the kiln.

By the employment of the means to be described hereinafter, the gas produced in a producer chamber or compartment of each kiln passes directly into the kiln behind the bag wall, where it may be further mixed with additional air and burned. The gas passing out of the producer chamber is thus mixed with a regulated supply of air under pressure, and the products of combustion pass directly into the body of the kiln from which the exhaust gas passes out through a stack in the usual manner, after the ware has been burned.

The difficulty of burning producer gas in a cold furnace is well known, but such difficulty is removed by means of the individual gas unit producer, which at the

beginning of the operation can be employed as a furnace until the kiln is brought to a sufficient temperature to burn the gas, and when this is done, the furnace is converted into a gas producer chamber or compartment, by closing the front portion and using sufficient air through the twyers to cause sufficient combustion to distil the gas out of the coal, and by employing the secondary air siphon to draw air to the point where the combustion is desired in the kiln.

The preferred form of embodiment of my invention is illustrated in the accompanying drawings of which Figure —1— is a side elevation in section, showing a portion of a kiln, and furnace or gas producer structure combined therewith. Fig. —2— is a perspective view of the portable twyer and supporting table. In this view one of the twyer supporting plates or bars is shown in a dumping position. And Fig. —3— is an end view, partly in section of one of the tilting twyer supporting plates or bars.

Throughout the specification and drawings similar reference characters indicate corresponding parts.

Referring to the accompanying drawings in more particular terms, the numeral —1— designates the inclosing wall of a combined furnace and gas producer chamber or compartment which is combined with the front portion of the kiln structure —2—. The said chamber is a part of the kiln structure by being built in the wall thereof and is provided with a suitable communication between the said chamber and the interior of the kiln. Formed in the kiln by the bag wall —3— is a combustion or mixing chamber —4— that connects with the furnace and gas producer chamber through an opening or conduit —5— provided in the upper portion of the wall —6— of the kiln. This conduit —5— forms the connection between the furnace and the gas producer chamber, and the combustion or mixing chamber —4— of the kiln. When the furnace or gas producer chamber is used as a gas producer, the conduit —5— directs the gas to a point in the combustion or mixing chamber —4— where combustion is effected by a forced draft of additional air, that is conducted to the latter through a supplemental air supply tube —7—.

Projecting into the outer open end of the tube 7, is a nozzle 8 connected to a vertical

tube 9 that communicates with a main air line 10, from which air under pressure is received to effect combustion of the producer gas in the chamber 4.

5 By means of a valve 11 provided in the vertical tube 9, the supply of air under pressure for the combustion chamber 4 can be regulated. Accordingly, to effect a greater or a less combustion of the producer gas in the chamber 4, air can be admitted to the latter under a greater or a less pressure by operating the control valve 11. (See Fig. 1).

Coming now to a detailed description of the furnace and gas producer chamber 1, 15 there is provided in the upper front portion thereof an opening 12 that is closed by a hinged door 13 provided with a handle 14. In the lower portion of the furnace and gas producer chamber 1 is an opening 15 that 20 is closed by a residue door 16 provided with a handle 17.

Through the opening 15 in the lower portion of the furnace, a twyer supporting-table is adapted to be inserted and removed.

25 By providing this table with two hinged front legs 19 and two rear hinged legs 20 connected by hinged bracing members 21, it is collapsible for the purpose of being easily transported from the furnace and gas 30 producer chamber of one kiln to that of another. (See Figs. 1 and 2). Accordingly, one of my twyer-supporting-tables by being portable, may be made to serve several kilns. The twyer-supporting table may be 35 readily withdrawn through the opening 15, and easily inserted through said opening in another furnace or furnaces to serve them when desired.

The table 18 preferably contains two 40 twyer supporting-plates 22 disposed side by side in the direction of its length in the upper portion of said table. While I have shown two of these plates, any greater or less number may be provided without departing from the spirit of my invention.

45 Each table plate 22 at its front and its rear end, and at one side of its longitudinal axis, has a trunnion 23 turning in a bearing 24 provided in the table frame. Each front 50 trunnion 23 terminates in a nipple and has a squared portion 25 that terminates at its rear end in a ratchet disk 26. The latter has provided in its periphery a notch 27 in which the nose of a pawl 28 pivoted to the 55 table 18, is adapted to fall by gravity to hold its respective plate 22 in a horizontal position. By means of a wrench applied to the squared portion 25 of the front trunnion 23, the latter may be turned a sufficient distance 60 to release its respective pawl 28, which will permit its respective plate 22 to tilt as shown in Fig. 2, to dump the ashes as will be hereinafter described.

65 Preferably mounted in two parallel rows upon each plate or tiltable member 22, are

twyers 29 whose tops at each end project outwardly and downwardly a short distance to protect the air openings 30 below, against being clogged by clinkers or other particles.

70

Accordingly, to effect a greater or a less combustion of the producer gas in the chamber 4, air can be admitted to the latter under a greater or a less pressure by operating the control valve 11. (See Fig. 1).

Coming now to a detailed description of the furnace and gas producer chamber 1, 15 there is provided in the upper front portion thereof an opening 12 that is closed by a hinged door 13 provided with a handle 14. In the lower portion of the furnace and gas producer chamber 1 is an opening 15 that 20 is closed by a residue door 16 provided with a handle 17.

Through the opening 15 in the lower portion of the furnace, a twyer supporting-table is adapted to be inserted and removed.

25 By providing this table with two hinged front legs 19 and two rear hinged legs 20 connected by hinged bracing members 21, it is collapsible for the purpose of being easily transported from the furnace and gas 30 producer chamber of one kiln to that of another. (See Figs. 1 and 2). Accordingly, one of my twyer-supporting-tables by being portable, may be made to serve several kilns. The twyer-supporting table may be 35 readily withdrawn through the opening 15, and easily inserted through said opening in another furnace or furnaces to serve them when desired.

By tilting the members 22 as hereinbefore described, the ashes may be readily dumped 95 from them.

When the furnace is used as a gas-producer for a kiln of which it is a part, it may be operated as a furnace and gas producer chamber for a short time as above described, to bring the kiln to a sufficient temperature to heat the gas. When this is done, the furnace is converted into a producer by closing its front portion and turning the valve 32 to permit only enough air to issue through the twyers to cause sufficient combustion to distil the gas out of the coal. The gas produced will then pass through the conduit 5 into the combustion chamber 4 of the kiln, where it is mixed with a regulated supply of air under pressure that issues from the tube 7. By turning the valve 11, the pressure of this secondary air supply can be regulated to produce the character of combustion desired for the kiln. It is thus seen that this secondary air siphon device carries air to the point where combustion is desired in the kiln, the gas being produced in the kiln's own furnace, with all the advantages hereinbefore set forth.

Among the advantages of my improved individual gas producer features in kilns may be mentioned the following:

(1) After the twyer as a whole is removed from one furnace and gas producer chamber to another, the said chamber, after the ware has been burned in the kiln, supplies sufficient air to the kiln for cooling the burned ware.

(2) The means are simple and kilns 130

already in use may be provided therewith at comparatively small cost. (3) The loss or dissipation of effective heat through radiation where the heat is controlled through 5 tunnels which connect the kilns with large gas producer units is avoided. (4) As compared to other gas burning systems with which I am familiar, a substantial portion of the cost of installation is eliminated.

10 (5) The danger due to gas explosions is very materially avoided, since there is no chance for the accumulation of gas in quantities, the gas being burned as soon as it enters the kiln from the producer chamber;

15 and other advantages might be enumerated.

Having described my invention, I claim:

1. In a kiln provided with a stationary furnace and gas producer chamber, and a conduit forming a passageway from said 20 chamber to the combustion chamber of the kiln, and an auxiliary air conduit through which additional air is supplied to the combustion chamber, a portable grate including a series of hollow tilting bars with 25 nozzles through which steam and air are injected into said bars, a series of twyers mounted on each bar and having air passages communicating with the interior of said bars, and an individual steam injecting 30 nozzle extended into the nozzle of each of said bars, substantially as described.

2. A series of kilns provided each with

a stationary furnace and gas producer chamber, a conduit forming a communication between said chamber and the combustion chamber of the kiln, and a supplementary air conduit to supply air to said combustion chamber, a portable grate adapted to be removed from the furnace and gas producer chamber of one kiln to that of another in the successive generation of gas, 35 said grate comprising a series of hollow bars the front ends of which terminate in nozzles adapted to receive steam and air, and a series of twyers supported on each of said bars, 40 substantially as specified.

3. A kiln having a bag-wall and a combustion chamber behind said bag-wall, and a combined individual furnace and gas producer chamber forming a unitary part of 50 the kiln structure, the upper part of said furnace and gas producer chamber communicating with said combustion chamber, and a portable gas producer element comprising a series of twyers supported on parallel hollow bars and adapted to be successively placed in the furnace and gas producer 55 chambers of a series of kilns of like structure, substantially as described.

In testimony whereof I have hereunto set 60 my hand this 7th day of March, 1919.

LOIS M. UNDERWOOD.
